UNITED STATES PATENT OFFICE.

FISEL KIMCHE, OF DETROIT, MICHIGAN.

PIPE-FITTING.

No. 853,413.

Specification of Letters Patent.

Patented May 14, 1907.

Application filed November 10, 1906. Serial No. 342,895.

To all whom it may concern:

Be it known that I, FISEL KIMCHE, a citizen of the United States of America, residing at Detroit, in the county of Wayne and State of Michigan, have invented certain new and useful Improvements in Pipe-Fittings, of which the following is a specification, reference being had therein to the accompanying drawings.

10 It is the object of the invention to obtain a fitting especially designed for use in bath rooms, to which all of the drain connections may be easily and quickly attached, and which will conform to all the sanitary requirements in force in many municipalities at the present day.

To this end, the invention consists in the peculiar constructions of a tee or cross pipe fitting, as hereinafter set forth.

20 In the drawings, Figure 1 is a side elevation of the fitting; Fig. 2 is a plan view thereof; Fig. 3 is a cross section on line $x-x$, Fig. 1; and Fig. 4 is a view similar to Fig. 1 illustrating a modification.

25 In general construction, my improved fitting comprises a vertical pipe section A of a suitable size to form the soil pipe of a closet, and one or more integral laterally extending pipe arms B, to which the various pipe connections are attached. As illustrated in Fig. 1, the arm B is provided at its outer end with an up-turned elbow C, adapted for direct connection with the closet. Intermediate this elbow in the pipe section A are laterally extending nipples for connecting with the other drain pipes, such as that of a washstand and a bath tub. I preferably provide two of these nipples D and E extending oppositely from the upper portion of the 35 pipe arm B. Thus, in use, the vertical section A may be arranged conveniently for connection with the downwardly extending soil pipe, and at its upper end is connected to the upwardly extending air vent pipe.

40 The upper and lower ends of this section A, F and G, are suitably fashioned for connection with the adjoining pipe sections, the one forming the socket member, and the other a member for fitting the socket of an 45 adjacent pipe.

The construction as thus far described is adapted for use in an ordinary house bath room, and when the various drain connections are attached, an absolutely tight system will be formed. If, however, the fitting 55 is used in flats or other places where connec-

tions are to be made on different floors with a common vertically extending soil pipe, the section A is connected into this pipe to form a portion thereof. For such a use, it is necessary to provide a separate vent connection, and to this end a nipple is formed at the intersection of section A with the upper side of the arm B, as illustrated at H. To this nipple a vent pipe may be attached, which 60 can be arranged parallel to the vertical soil pipe.

In Fig. 4 is illustrated the construction in which there is a second laterally extending arm I formed integral with the section A, 70 and preferably directly opposite the arm B. This arm is adapted for connection with a laterally extending soil pipe from another closet where there are more than one upon the same floor.

75 The socket member F, in addition to its function as a coupling with the upwardly extending pipe, also forms a support for the fitting upon the floor. As illustrated in Fig. 1, the shoulder F' is adapted to rest directly 80 upon the floor and support the fitting between the floor and the ceiling of the lower room.

In order to provide proper drainage, the laterally extending arm B is provided with 85 a downward inclination from the upturned elbow to the vertical section A. To prevent interference with the vent connection, by reason of this downward inclination, the upper portion of the arm is provided with a 90 channel I', which is inclined upwardly from the elbow to the vertical pipe. The laterally extending nipples D and E intersect the arm B in the upper portion thereof, and thus communicate both with the said pipe and 95 the channel I' thereof.

What I claim as my invention is:

1. A pipe fitting comprising a vertical pipe section, an integral laterally extending pipe arm terminating in an upturned elbow, and 100 one or more connections to said arm intermediate said elbow and the vertical section, said arm having a vent channel therein communicating with said connections.

2. A pipe fitting comprising a vertical section, an integral laterally extending pipe arm terminating in an upturned elbow and oppositely laterally extending nipples or pipe connections on said arm intermediate said elbow and the vertical pipe section, said arm having 110 a vent channel communicating with said nipples.

3. A pipe fitting comprising a vertical pipe section, an integral laterally extending pipe arm terminating in an upturned elbow, a laterally extending nipple or pipe connection on said arm, said arm having a vent channel opening from said nipple and a nipple or pipe connection for the connection of said channel with a vent pipe.
4. A pipe fitting comprising a vertical pipe section, oppositely laterally extending pipe arms integral with said vertical section, one of said arms terminating in an upturned elbow, one or more laterally extending nipples or pipe connections on one of said arms and a vent connection leading from said nipples, for the purpose described.
5. A pipe fitting comprising a vertical pipe section, an integral laterally extending pipe arm terminating in an upturned elbow, one or more pipe connections to said arm intermediate said elbow and the vertical section, a vent connection communicating with said pipe connections and a socket coupling formed at the upper end of the vertical section having a shoulder forming a support for the fitting.
6. A pipe fitting comprising a vertical pipe section, an integral laterally extending pipe arm terminating in an upturned elbow and inclined downwardly from said elbow to said vertical section, the upper position of said arm being provided with a channeled portion forming a vent inclined upwardly from the elbow to the vertical section.
7. A pipe fitting comprising a vertical pipe section, an integral laterally extending pipe arm terminating in an upturned elbow, said arm being inclined downwardly from said elbow to said vertical section, a channeled ex-
- 5 tension of said arm forming a vent inclined 40 upwardly from said elbow to said vertical section, and a connection extending laterally from said arm intersecting the same in direct communication with said channel.
8. The combination with a vertical pipe, of 45 a laterally-extending pipe connected therewith, and terminating in an up-turned elbow, a pipe connected with said laterally-extending portion intermediate said elbow and vertical pipe, and a channel forming a constant 50 air communication between the last mentioned pipe and said vertical pipe, said channel being formed within the upper portion of said laterally-extending pipe.
9. The combination with a vertical pipe, of 55 a laterally-extending pipe connected therewith, and terminating in an up-turned elbow, a channel within said laterally-extending pipe above the level of the elbow and communicating with said vertical pipe, and a 60 nipple on said laterally-extending pipe forming a connection in constant communication with said air channel.
10. A pipe fitting comprising an elbow having a laterally-extending arm, a channel 65 formed in and extending longitudinally of said lateral arm above the level of its communication with the vertical portion of the elbow, and a pipe connecting with said lateral arm in direct communication with said channel.

In testimony whereof I affix my signature in presence of two witnesses.

FISEL KIMCHE.
